UNITED STATES PATENT OFFICE

HARRY L. STRAND, OF BOSTON, MASSACHUSETTS

TITLE BLOCK AND WALL CONSTRUCTION

Application filed December 7, 1925. Serial No. 73,624.

This invention relates to terra cotta or hollow tile building blocks used particularly in backings for brick walls or veneers, an object of the invention being to provide an improved hollow tile block and wall construction wherein the tile block may be relatively cheap and light in construction and at the same time having increased supporting strength. The invention relates to that type 10 of building block and wall shown and described in my co-pending application Serial No. 43,839 filed July 15, 1925.

According to the present invention the tile block is constructed with a central or interior 15 supporting web or wall to which, when vertically disposed, vertical stresses in a plurality of vertical planes may be transmitted directly to the web, this being accomplished in the present instance by means of 20 converging web portions. As a result of the improved construction the weight from the floor beams or joists is directly taken up or transmitted by the vertical walls and web of the block, and the weight transmitted 25 through the header courses of brick and the tile filler blocks to the building block is also transmitted directly to the vertically disposed side walls and central supporting web thereof.

In addition to the foregoing the present 30 improved hollow tile is constructed so that the necessity, as heretofore of trimming down or shattering the block by workmen, due to variations in size on account of variations in burning, is entirely done away with. The 35 improved tile block of this invention is provided with a pair of opposite approximately square walls, joined together preferably by a pair of opposite rectangular walls, each square wall having a dimension modified from the normal or standard dimension of the square wall 40 by an amount sufficient to compensate for variations in the burning of the block. As a result of this construction therefore when the workmen in building the wall encounter a 45 low burned tile block which sticks up or projects above the adjacent blocks, it is merely necessary for him to turn the block over so that the other dimension of the square wall will approximate the proper height of 50 the block. Heretofore where the workman

encountered a low burned tile which projected too high in the wall, it was necessary for him to trim or break off the top of the block in order to bring the tops of all of the blocks on a level.

Other objects of the present invention will appear in the following description and appended claims, reference being had to the accompanying drawings forming a part of this specification wherein like reference characters 55 designate corresponding parts in the several views, and wherein:

Fig. 1 is a fragmentary perspective view illustrating a type of wall construction embodying my invention.

Fig. 2 is a vertical section through a wall.

Fig. 3 is a perspective view of one form of my improved building block.

Fig. 4 is a perspective view of a T-shaped 60 filler block.

Fig. 5 is a perspective view of another form of filler block.

Fig. 6 is an end elevation illustrating another form of block embodying my invention.

Fig. 7 is a fragmentary perspective view illustrating a type of wall construction.

Before explaining in detail the present improvement and of construction thereof, I desire to have it understood that the invention is not limited to the details of construction and arrangement of parts which are illustrated in the accompanying drawings, since the invention is capable of other embodiments, and that the phraseology which I employ is for the purpose of description and not of limitation.

In the present instance the hollow tile building block A, B, or C is constructed with a pair of opposite substantially square solid walls 9 and 10, these walls being joined together at their opposite ends by means of a pair of solid outer walls 11 and 12. The block in the preferred construction thereof is provided with four chambers or air passages a, b, c and d which are formed by means of interior intersecting webs or walls 13 and 14. Referring to Figs. 2, 3 and 7 the central supporting web 14 terminates at opposite ends in a pair of inclined 100

web portions 15 and 16 joined to the opposite outer walls 11 and 12. The webs 15 and 16 as shown in the drawing extend at oblique angles with relation to each other and form 5 therebetween a V-shaped chamber or air passage closed by means of the walls 11 and 12.

Referring to Fig. 2, in the type of wall construction shown therein the brick veneer or facing of the wall may comprise a series of 10 five brick courses 17, the dimension of the square walls 9 and 10 of the block A corresponding substantially to the five brick courses 17. The wall also comprises a header course of brick 18 which extends in overlapping relation upon the building block A and is supported by the web 16 and one of the vertical walls 9. A filler block 19 is located in rear of the header course 18, and it will be seen that the vertical walls 19^a and 19^b of 15 this filler block are supported by the web portion 15 and the opposite vertical wall 10 of the block. A floor beam or joist 20 is shown in position upon the building block and is supported by means of the inclined webs 15 and 20 16 and the wall 10 of the block. From this construction, with the building block and the filler block positioned in the manner shown in Fig. 2, it will be seen that the header course 25 of brick 18 has a direct vertical bearing on one of the inclined webs 16 and upon an outer wall 9 of the block. In addition the walls 19^a and 19^b of the filler block have a direct vertical bearing upon the other inclined web 15 and the opposite wall 10 of the block. This construction in addition provides an air passage 35 between the header course 18 and the course of filler blocks 19. The converging or inclined webs 15 and 16 transmit the stresses inwardly to the central supporting web 14, so that as a result the vertical stresses at points intermediate the vertical plane of web 14 and the vertical planes of walls 9 and 10 are transmitted directly to the web 14. Also it will be seen that the weight of the floor beam 20 40 is carried by both of the webs 15 and 16 and the wall 10, and the weight sustained by the inclined webs 15 and 16 is directly transmitted to the central supporting web 14.

In the type of wall construction shown in 50 Fig. 1 the building block is provided with divided or spaced wall sections 12a and 12b forming a longitudinal air space or passage 21. In this construction the central web 14 terminates in a pair of outwardly inclined webs 15 and 16 which are joined to the adjacent longitudinal edges of the wall sections 12^a and 12^b, thus forming at the two opposite 55 sides of the block lengthwise extending open air passages 21. This construction has the advantage of doing away with a solid or continuous mortar joint through the wall, and prevents the transmission of moisture through the wall. In this type of wall shown in Fig. 60 1 a T-shaped filler block 22 is employed, which comprises a relatively long portion 22^a

and a shorter portion 22^b connected together by a web 22^c. When the building block and the filler block 22 are in position as illustrated, the opposite vertical walls 23 and 24 of the longer section of the filler block have a direct vertical bearing upon the wall 10 and the inclined web 15, and the opposite vertical walls 25 and 26 of the smaller section of the filler block have a direct vertical bearing upon the web 16 and the opposite wall 9 of the building block. Thus the weight or stress transmitted through the walls 23 and 26 of the filler block is sustained by the opposite walls 9 and 10 of the building block, and the weight or stresses transmitted through the intermediate walls 24 and 25 is taken up directly by the converging webs 15 and 16 and thereby transmitted to the single supporting web 14 of the block. 70 75 80 85

Referring to the construction shown in Fig. 6, it will be seen that the central supporting web 14 of the block C is joined at each end to one of the walls 11 or 12 of the tile block by means of three angularly related web portions 28, 29 and 30. It will be seen therefore that a block constructed in this manner will transmit directly to the central web 27 vertical stresses upon the wall 11 or 12 at three points between the walls 9 and 10. 90

Each of the walls 9 and 10 of the block A, B or C is approximately square, the dimensions thereof being varied slightly so as to compensate for variations in the burning of the tile. It is a well known fact that in the burning of the tile block some blocks are necessarily placed nearer the fire than others and it therefore follows that some blocks are burned to a greater degree than others resulting in the production of so-called low-burned tiles and hard-burned tiles. The lowburned tile contracts less than the hard-burned tile and therefore the size thereof will be somewhat greater. Heretofore in the building of a wall, when the workmen encountered a low-burned tile which projected above the level of the other blocks of the course, it was necessary for him to trim or break off the top of the block so as to bring it on a level with the tops of adjacent blocks. This practice required considerable labor and not only resulted in increasing the cost of the building 100 but also in materially weakening the block and therefore weakening the wall. It was necessary after trimming down and breaking off the top of the block to patch it up with mortar, which resulted in a large number of 105 defective blocks in the wall. The present improved building block on the other hand eliminates all of these disadvantages. One of the dimensions as 9^a, see Fig. 3, of the square wall 9 may be constructed slightly shorter 110 than the normal or standard dimension for this square wall, and the transverse dimension 9^b may be constructed so as to be slightly longer than the normal or standard dimension. After burning if the block turns out 115 120 125 130

to be a low-burned tile, the dimension 9^a will closely approximate the correct dimension of the block. If, on the other hand, it is a hard-burned tile and has contracted more in the burning process, the dimension 9^b will closely 5 approximate the correct or normal dimension. As a result therefore, when the workman encounters a low-burned tile of my invention, if the block, as positioned in Fig. 3 10 with the edge 9^b in a vertical position, projects too high in the wall, it is merely necessary for him to turn the block over so that the edge 9^a will extend vertically. Since the dimension 9^a is constructed slightly less than 15 the normal dimension, the lesser contraction of the block during burning will cause this dimension to approximate the normal or standard dimension.

According to the present invention the 20 filler block 19 shown in Fig. 5 has a length substantially corresponding to the normal or standard dimension of the square wall 9. Therefore, referring to the wall construction 25 shown in Fig. 7 when the floor beam 20 is in position and interposed between a pair of adjacent tile blocks of a course, one thereof shown at A, the filler block 19 may be utilized to occupy the space between such blocks by 30 turning the filler block into a vertical position. The filler block will be supported by one of the bricks of the header course 18 at the end of the beam 20 and since the filler block has a length substantially the same as the dimensions of the square wall 9 the top 35 of the filler block will be on a level with the adjacent building block irrespective of whether it is a low-burned or a hard-burned tile. The relation of the filler block to the improved tile block A, B or C therefor enables its use in various positions, avoids the 40 necessity of breaking up blocks for fillers or using mortar fillers, and provides a stronger wall.

It is to be understood that by describing 45 herein any particular form, structure, or arrangement, it is not intended to limit the invention beyond the terms of the several claims or the requirements of the prior art.

What I claim is:

50 1. A wall construction comprising a brick facing composed of superimposed bonded face courses of brick, a hollow building block forming a backing for said face courses and having in one position thereof three continuous vertical webs parallel to the face of the wall, one thereof substantially centrally located with respect to the outer faces of the block, a pair of relatively shorter inclined webs diverging from said central web upwardly and joined to a top wall of the block, a header course of brick supported in part 55 on said block and in part on the face courses, a filler block in rear of the header course and supported on said building block, the latter 60 having a pair of said webs joined to the top

wall at points in substantial vertical alignment with a pair of opposite vertical walls of the filler block, and also having another pair of said webs directly supporting the brick header course. 70

2. A wall construction comprising a brick facing composed of superimposed bonded face courses of brick, a hollow building block forming a backing for said face courses and having in one position thereof a pair of outer vertical webs and an interior vertical web joined to a top wall of the block by a pair of shorter upwardly diverging web portions, a header course of brick supported in part on said block and in part on the face courses, a 75 T-shaped filler block supported on said building block in rear of the header course and comprising a relatively long portion and a shorter portion, each of said portions of the filler block having a pair of vertical webs 80 bearing on one of said web portions and on one of said outer vertical webs. 85

3. In a wall construction of the type having a brick facing composed of superimposed bonded face courses of brick and a header course of brick supported in part on said face courses, a hollow building block forming a backing for said face courses and in part supporting said header course, and a T-shaped filler block comprising a relatively 90 long portion and a shorter portion joined in the same horizontal plane and having substantially the height of said header course, said header course extending at three sides 95 of said shorter portion of the filler block. 100

In testimony whereof I affix my signature.
